CONVEYOR

Harry E. Ziegler, Chardon, Ohio, assignor to May-Fran Manufacturing Co., Cleveland, Ohio, a corporation of Ohio

Filed Oct. 11, 1967, Ser. No. 8,958

Term of patent 14 years

Int. Cl. D12—05

U.S. Cl. D55—1

FIG.1

FIG.2

FIG.3

FIG.4

FIGURE 1 is a perspective view of a conveyor embodying my new design;

FIGURE 2 is a side elevation thereof;

FIGURE 3 is a right end elevation thereof; and,

FIGURE 4 is a top plan thereof.

From the showings of FIGURES 1-4 the side of the conveyor opposite from the side shown in FIGURE 2, is a mirror image of FIGURE 2.

I claim:

The ornamental design for a conveyor, substantially as shown and described.
